UNITED STATES PATENT OFFICE.

JOHN W. DARLEY, JR., OF BALTIMORE, MARYLAND.

FUSE FOR PROJECTILES.

1,351,416.

Specification of Letters Patent. Patented Aug. 31, 1920.

Application filed May 12, 1915. Serial No. 27,616.

To all whom it may concern:

Be it known that I, JOHN W. DARLEY, Jr., a citizen of the United States, residing at Baltimore, in the State of Maryland, have 5 invented certain new and useful Improvements in Fuses for Projectiles, of which the following is a specification.

My invention relates to fuses for projectiles, and the object of my invention is to 10 produce a fuse, the firing pin of which shall be normally locked, which shall be unlocked when the speed of rotation of the projectile exceeds a predetermined limit, and which afterward shall fire the explosive contained 15 in the projectile when the speed of said projectile diminishes below a predetermined limit.

By constructing a fuse to operate in this manner, I am enabled to explode a projectile 20 under water even though it should not strike a solid object, and thus the projectile is rendered an effective weapon against submarine boats.

The fuse herein shown and described, is 25 intended for use with a special form of projectile adapted for use against submarine boats as shown and described in my application for Letters Patent filed on even date herewith.

30 Said projectile is intended to rotate on an axis at right angles to the trajectory and in such a direction as to eliminate or greatly diminish the upward resistance of the water, whereby ricochetting is prevented and the 35 projectile can be exploded after passing through a certain length of path of water, owing to the skin friction reducing the speed of rotation of the projectile to the limit at which my new fuse acts. Hence the projectile 40 will explode if it strikes a submarine or if not, it will explode as just described, because in both cases the speed of rotation will be reduced to the proper limit. Such a projectile equipped with my new fuse is thus 45 an effective weapon against a submarine, because an explosion can be produced against the hull or in the neighborhood thereof, thus increasing the dangerous space.

The fuse herein shown and described, 50 however, is capable of use with any form of projectile, providing that it has a motion of rotation.

In whatever form of projectile used, the

longitudinal axis of the fuse is to be substantially in line with the axis of rotation 55 of the projectile.

In the drawings:

Figure 1 is a side view of my improved fuse;

Fig. 2 is a front view thereof; 60

Fig. 3 is a section along the line 3, 3 of Fig. 2, looking in the direction of the arrow.

Fig. 13 is a rear view of the front cap; 75

Fig. 14 is a longitudinal central section of the part shown in Fig. 13; and

Fig. 15 is a front view of the front cap.

Fig. 16 is a side view of the projectile with which my improved fuse is preferably used, 80 and

Fig. 17 is a central section of the projectile shown in Fig. 16.

20 is a casing of any suitable metal provided with screw threads 21, 22 and 23. By 85 means of the thread 22 the fuse is to be screwed into the projectile.

Any type of projectile that has a motion of revolution can be used with my improved fuse, but said fuse is preferably used with 90 the type of projectile shown in Figs. 16 and 17 and fully described in my application for U. S. Letters Patent filed on even date herewith.

Referring to said figures, said projectile 95 consists of the spherical body 79 having a groove 80 therein in which is shrunk a copper zone 81.

Said projectile is intended to be fired from a special type of gun, shown in said application for U. S. Letters Patent, so that it will rotate around the axis passing through the center of the casing 20, said axis being preferably horizontal and at right angles to the trajectory. 100

Said projectile may be so rotated, with 105

its forward surface moving downwardly when it is desired to prevent the shell from ricochetting when it strikes the surface of the sea or when it is desired to have a trajectory incurvated downwardly for attacking positions behind obstructions.

Should it be desired to cause the projectile to ricochet from the surface of the sea, then it is to be rotated with its forward surface moving upwardly.

When the projectile is fired with its forward surface moving upwardly the reaction of its surface with the air will act contrary to the force of gravity and tend to flatten the trajectory or even cause it to be incurvated upwardly.

The projectile may be fired with its axis at any angle to the horizontal to cause said trajectory to be incurvated to varying degrees either to the right or left.

The rear end of the casing 20 is closed by a rear end cap 24, provided with a recess containing priming powder 25. The cap 24 is provided with a neck 26 upon which is secured a detonating cap 27.

The interior of the casing 20 is cylindrical in form excepting for the tapered part 28, which is to receive the tapered part 29 of the guide 30. The guide is metal and the body 31 is cylindrical in shape and fits snugly in the interior of the casing 20.

A hole 32 extends from the rear end of the body 31 of the guide toward the front of same, to the line 33 which is in line with the juncture of the tapered portion 29 and the cylindrical portion 31. The hole 32 is formed by the flat sides 34, 34 and the semi-cylindrical ends 35, 35.

From the line 33 to the front of the guide 30 the cylindrical hole 36 extends axially and two slots 38, 38 extend radially from this hole. Slots 39, 39 are cut radially across the front of the guide 30.

The firing pin, shown in Figs. 7, 8 and 9, is formed of metal, and consists of the cylindrical portion 40, provided with a flange 41 having a beveled edge 42.

The cylindrical portion 40 is further provided with a flange 43 having the holes 44. A cylindrical guide 45, which is of a diameter to fit loosely in the interior of the casing 20, joins the flange 43 and is provided with a front flange 46. A cylindrical hole 47 extends from the front end of the firing pin to the flange 43; all parts of the firing pin are formed of one piece of metal.

The detent shown in Figs. 10, 11 and 12 is preferably formed of high grade steel and provided with a spring temper. It is formed from a piece of steel of the proper diameter and length by boring a cylindrical hole 48 from the front end 50 to the inner face 49 of the pawls 51. The body is then turned cylindrical between the lugs 52 and pawls 51, leaving cylindrical flanges on the

ends of said piece of steel of the thickness respectively of the pawls 51 and lugs 52. The pawls 51 are then countersunk as at 53, and a slot 54 is milled through the pawls to the hole 48. The outer portions of the end flanges are then milled off to shape the outer portions of the pawls 51, and the lugs 52.

Slots 55 and 68 are then cut through the cylindrical portions of the detent, thus leaving a fastening portion 56, provided with the lugs 52, two spring portions 57, and two weighted portions 58 provided with the pawls 51.

The front end cap shown in Figs. 13, 14 and 15 consists of the body 59, provided with the screw threads 60 and 63 and the cylindrical neck portion 61 having the cylindrical hole 62. The neck portion 61 is to be a snug fit in the hole 48 of the detent, and the portion 40 of the firing pin is to slide freely in the hole 62. The screw thread 63 is to fit the screw thread 23 of the casing 20.

In assembling my fuse, the detent as shown in Fig. 11, is to have its lugs 52 passed from the left toward the right through the hole 32 and slots 38 of the guide, shown in Fig. 5, until the lugs 52 are clear of the front face of the guide, the latter is then to be revolved 90 degrees to bring the slots 39 opposite the lugs 52, then the detent 95 is to be moved toward the left to bring the lugs 52 into the slot 39. The fastening portion 56 of the detent will then fit snugly in the hole 36.

The guide body 31, carrying the detent is 100 then to be forced into the casing 20. The front end cap is then to be screwed into place, then its portion 61 will enter the hole 48 of the detent and its portion 59 will force the taper 29 of the guide into firm engagement with the taper 28 of the casing.

It is obvious that with this construction, the casing 20, the guide 30 and the detent portion 56 and lugs 52 are all firmly locked together, that the weighted portions 58 of the detent can move outwardly in the hole 32, but that the flat sides 34 of said hole prevent any lateral motion of said weighted portions 58.

The firing pin is then to be introduced into the rear end of the casing and its cylindrical portion 40 is to have its front end introduced into the hole 62 of the front cap. During this movement of the firing pin toward the position shown in Fig. 3, the beveled edge 42 will strike the countersunk portions 53 of the detent and cause pawls 51 to lift over the flange 41, and then these parts will assume the relative positions shown in Fig. 3.

The rear end cap 24 is then to be screwed into place. Holes as 64 are provided in the casing 20 and the end caps 24 and 59 for the application of suitable wrenches.

The casing 20 can then be screwed into the

projectile, the spring 65 introduced into the hole 47 of the firing pin through the threaded hole 60 of the front cap and the screw 66 screwed into place. The screw 66 5 has a tip 67 which fits loosely on the inside of the spring 65.

The spring 65 and screw 66 may be placed in position just before the projectile is fired if preferred.

- 10 The operation of my improved fuse is as follows—The normal position of the parts is as shown in Fig. 3, with the spring 65 tending to push the firing pin toward the left, but prevented from so doing because the 15 flange 41 of the firing pin is locked by the pawls 51.

When the projectile is fired, the revolution thereof will cause the pawls 51 to move outwardly under the influence of the centrifugal force on the weighted portions 58, thus releasing the flange 41. The spring 65 will then move the firing pin toward the left until the flange 46 strikes the outer ends of the pawls 51, thus holding the firing pin 25 until the speed of the revolution of the projectile has decreased to such a degree that the inward stress of the spring portions 57 will cause the pawls 51 to release the flange 46. When this happens the spring 65 forces 30 the firing pin against the fulminating cap 27 and explodes the projectile.

I claim:

1. The combination with a casing of a detonating cap and means carried by said 35 casing for detonating said cap when the speed of rotation of said casing decreases below a predetermined high speed.

2. The combination with a casing of a detonating cap, a firing pin, means for normally locking said firing pin, and means for forcing said pin against said cap when the speed of rotation of said casing decreases below a predetermined high speed.

3. The combination with a casing of a detonating cap, a firing pin, means for normally locking said firing pin, means for unlocking said pin when the speed of rotation of said casing decreases below a predetermined high speed, and means for forcing 50 said pin against said cap.

4. The combination with a casing of a detent, a firing pin having two members for coöperating with said detent, said detent being so constructed and arranged that said 55 detent normally locks one of said members, then unlocks said member and locks the second member when the speed of rotation of said casing increases above a predetermined limit, and then unlocks said second member, 60 when the speed of rotation of said casing diminishes below a predetermined limit.

5. The combination of a casing with a detonating cap, means for firing said cap, means for normally locking said firing 65 means, means for unlocking said firing

means when the speed of rotation of said casing diminishes below a predetermined high speed.

6. The combination with a casing with a detonating cap, normally locked firing 70 means carried by said casing for firing said cap, unitary means for unlocking and again locking said firing means when the speed of rotation of said casing exceeds a predetermined speed and means for again unlocking 75 said firing means when said speed of rotation decreases below a predetermined speed.

7. The combination with a casing of a detonating cap, normally locked firing 80 means carried by said casing for firing said cap, unitary means for unlocking said firing means at a predetermined speed of rotation of said casing and obstructing the movement of said firing means toward said detonating 85 cap, and means for firing said cap when the speed of rotation of said casing decreases below a predetermined speed.

8. The combination with a casing of a detonating cap, a normally locked firing 90 pin, and unitary means operated by centrifugal force for unlocking and again locking said firing pin when the speed of rotation exceeds a predetermined speed and for again unlocking said firing pin when the 95 speed of rotation of said casing diminishes below a predetermined speed.

9. The combination with a casing of a detonating cap, a normally locked firing 100 pin, unitary means operated by centrifugal force for unlocking and again locking said firing pin when the speed of rotation exceeds a predetermined speed and for again unlocking said firing pin when the speed of rotation of said casing diminishes below a 105 predetermined speed, and means for forcing said firing pin against said cap.

10. The combination with a casing of a detonating cap, a firing pin, a weighted detent for normally locking said firing pin, 110 said detent being so constructed that it unlocks and then locks said firing pin when the speed of rotation increases beyond a predetermined speed and then unlocks said firing pin when the speed of rotation of said casing diminishes below a predetermined speed, and means for forcing said pin against said cap.

11. The combination with a casing of a detonating cap, a firing pin, a weighted detent and means on said firing pin coöperating therewith for normally locking said firing pin, said detent being so constructed that it unlocks said firing pin when the speed of rotation of said casing diminishes below a predetermined speed, and means for forcing said pin against said cap.

12. The combination with a casing of a detonating cap, a firing pin, a spring for forcing said pin against said cap, a flange 130

4
on said firing pin, a detent coöperating with said flange to normally lock said firing pin, a second flange on said firing pin coöperating with said detent to lock said firing pin 5 until the speed of rotation of said casing diminishes below a predetermined speed.

13. The combination with a projectile revolving on an axis at right angles to the trajectory, of an explosive charge contained 10 in said projectile and a fuse mounted in said projectile, said fuse comprising a firing pin, means for moving said pin, means for unlocking said pin when said shell is fired and means for forcing said pin against the 15 primer when the speed of rotation of said shell is reduced to a predetermined speed.

14. The combination with a projectile revolving on an axis at right angles to the trajectory, of an explosive charge contained 20 in said projectile, and a fuse mounted in said projectile with its axis in line with the axis of said projectile.

15. The combination with a projectile revolving on an axis at right angles to the trajectory, of an explosive charge contained 25 in said projectile, and a fuse comprising a detonating cap and means for firing said cap when the speed of rotation of said projectile diminishes below a predetermined speed. 30

16. The combination with a projectile revolving on an axis at right angles to the trajectory, of an explosive charge contained in said projectile, and a fuse comprising a detonating cap and means for firing said 35 cap when said projectile has traversed a predetermined length of water trajectory.

In testimony whereof I affix my signature in presence of two witnesses.
